UNITED STATES PATENT OFFICE.

WILLIAM P. DELANEY, OF AMSTERDAM, NEW YORK, ASSIGNOR OF ONE-HALF TO
WILLIAM W. DICKSON, OF AMSTERDAM, NEW YORK.

INK-FOUNTAIN FOR PRINTING-PRESSES.

1,155,710.

Specification of Letters Patent.

Patented Oct. 5, 1915.

Application filed October 6, 1913. Serial No. 793,502.

To all whom it may concern:

Be it known that I, WILLIAM P. DELANEY, a citizen of the United States, residing at Amsterdam, county of Montgomery, and 5 State of New York, have invented certain new and useful Improvements in Ink-Fountains for Printing-Presses, of which the following is a specification.

The invention relates to such improvements and consists of the novel construction and combination of parts hereinafter described and subsequently claimed.

Reference may be had to the accompanying drawings, which form a part of this 15 specification. Similar characters refer to similar parts in the several figures therein.

Figure 1 of the drawings is a top plan view of my improved ink-fountain. Fig. 2 is a vertical section of the same taken on the 20 broken line 2—2, in Fig. 1, through the axis of the ink-feeding roller. Fig. 3 is a view in side elevation of the same. Fig. 4 is a vertical cross-section of the same taken on the broken line 4—4 in Fig. 1.

25 Certain objects of the invention are to automatically supply ink to the ink-feeding apparatus directly from the original package or can; to avoid waste in the feeding of ink to a printing-press; to accurately regulate from time to time the amount of ink which the ink-feeding roller is permitted to carry from the fountain; to prevent accumulation of the ink upon the ink-feeding roller, and to facilitate cleansing the ink-feeding 30 apparatus.

Referring to the drawings wherein the invention is shown in its preferred form, 1, 40 represents an ink-feeding-roller such as is commonly employed in ink-fountains for feeding the ink from the fountain to the type-inking surfaces, which are not shown in the drawing. This feed-roller, 1, is rotatively mounted in bearings in the yoke-frame, 2, and is adapted to be rotated step by step by means of a ratchet-wheel, 3, in the 45 usual manner.

The ink is supplied to the feed-roller, 1, from a reservoir, 4, and a saddle-plate, 5, which plate is of segmental form adapted to receive and closely fit the upper half of the feed-roller, as shown in Fig. 4. The reservoir, 4, is in the form of a tube, the lower end of which communicates with an aperture, 6, in the saddle-plate, 5, through which aperture the ink passes down to the surface

of the feed-roll. The tubular reservoir, 4, is preferably made separable from the saddle-plate, 5, by means of a screw-connection at 7. The upper end of the reservoir-tube, 4, has a similar separable screw-connection at, 8, with a centrally-apertured plunger, 9, which is adapted to fit closely within the body of an inverted cam, 10, such as is ordinarily used as a container for printers' ink. In the use of the apparatus, 60 such a can of ink is inverted upon the plunger, 9, and its contents pass down through the central-opening, 11, in the plunger, and the reservoir, 4, and the aperture, 6, in the saddle-plate to the surface of the feed-roll. The can, 10, may be pressed down upon the plunger from time to time by hand or by any superimposed weight or pressure. When the last of the contents of the can has 65 passed down into the reservoir, 4, the empty 70 can is removed and replaced by a full can.

By making the reservoir, 4, readily separable at its opposite ends from the saddle-plate, 5, and the plunger, 9, when it is desired to use only a small quantity of ink the 80 plunger and reservoir can be detached from the saddle-plate, 5, and the inverted plunger forced down into an upright can of ink until the ink is forced up into the reservoir, 4, to the desired degree, whereupon the reservoir, 4, can be detached from the plunger, 9, and replaced upon the saddle-plate, 5, leaving 85 the plunger, 9, within the can, 10.

The saddle-plate, 5, is supported in adjustable relation to the feed-roller, 1, by 90 means of screw-threaded studs, 12, which project upward from the saddle-plate through open slots, 13, in a plate, 14, mounted by means of bolts, 15, upon brackets, 16, which extend upward from the yoke-frame, 95 2, the threaded portion of each of said studs, 11, having thereon a nut, 17, below the plate, 14, and a nut, 18, above said plate, 14. By proper adjustment of said nuts the saddle-plate, 5, can be adjustably raised or lowered 100 and then secured in the adjusted position by tightly clamping the plate, 14, between the nuts, 17 and 18.

When the saddle-plate, 5, is in its lowermost position, it practically rests upon and 105 substantially fits the surface of the feed-roller, so that when the feed-roller is rotated in the direction of the arrow, 19, as in use, it will carry or feed out from the fountain a thin film of ink of a width substantially the 110

same as the diameter of the aperture, 6. An upward movement of adjustment of the saddle-plate, 5, will cause its edge, past which the ink is carried by the feed-roll, to move slightly upward in a vertical plane tangential to the side of the feed-roll, causing a very gradual increase in the distance of separation of said edge from the surface of the feed-roll, so that a considerable upward movement of adjustment of the saddle-plate can be made with but slight increase in the thickness of the film of ink which is carried past said edge of the saddle-plate. Upward movement of adjustment of the saddle-plate, however, causes its surface, which is adjacent to the top of the feed-roll, to move directly upward away from the surface of the feed-roll, permitting the ink to flow lengthwise of the roll into the space thus opened up to increase the width of the film which is fed from the fountain by the feed-roll. By proper adjustment of the saddle-plate, 5, it is thus possible to accurately regulate the quantity of ink which is supplied by the feed-roll to the type-inking surfaces.

In order to prevent the ink from accumulating on the feed-roll, I have shown that part of the saddle-plate, 5, past which the surface of the feed-roll moves toward the reservoir, 4, provided with a groove, 21, leading to the aperture, 6, so that any ink remaining upon the feed-roll will not be scraped off therefrom, but will be guided back to the aperture 6.

In the preferred form of my invention, the aperture, 6, in the saddle-plate is located at one side of the vertical plane passing through the axis of the feed-roll whereby said aperture is located adjacent to the downwardly moving surface of the feed-roll, as shown in Fig. 4.

The saddle-plate, 5, is preferably provided with end-flanges, 20, which closely embrace the ends of the feed-roll and prevent escape of ink from the ends of the roll when the saddle-plate is adjusted in somewhat elevated position relatively to the roll.

What I claim as new and desire to secure by Letters Patent is—

1. In a device of the class described and in combination, an ink-feeding roll; a segmental saddle-plate substantially conforming to the upper side of said roll and provided with an aperture located substantially in rear of a vertical plane passing through the axis of the roll, said saddle-plate having inwardly extending end-flanges lapping and closely fitting the respective ends of the roll; and an ink-reservoir in communication with said aperture in said saddle-plate.

2. In a device of the class described and in combination, an ink-feeding roll; a segmental saddle-plate substantially conforming

to the upper side of the roll and extending on the rear side of the roll substantially to a horizontal plane passing through the axis of the roll, said saddle-plate being provided with an aperture open to the rear side of the roll substantially in rear of the vertical plane passing through the axis of the roll and having inwardly extending end-flanges lapping and closely fitting the respective ends of the roll.

3. In a device of the class described and in combination, an ink-feeding roll; a vertically adjustable segmental saddle-plate substantially conforming to the upper side of the roll and extending on the rear side of the roll substantially to a horizontal plane passing through the axis of the roll, the rear edge of said plate being adapted to make substantially rubbing contact with the roll, said plate being provided with an aperture located substantially in rear of a vertical plane passing through the axis of the roll, and with a groove in its under-surface adjacent to the front side of the roll leading to said aperture, and means for adjustably raising and lowering said saddle-plate.

4. In a device of the class described, and in combination, an ink-feeding roll; a substantially semicylindrical vertically adjustable apertured saddle-plate conforming to the upper half of said roll; an ink-reservoir communicating with said aperture in the saddle-plate; and means for fixedly supporting the saddle-plate in different positions of vertical adjustment.

5. In a device of the class described, and in combination, an ink-feeding roll; an apertured saddle-plate adjacent to the upper side of said roll; an apertured plunger; an open can-body inverted upon said plunger; and a tube having its lower end detachably connected with said saddle-plate in communication with the aperture therein and having its upper end detachably connected with said plunger in communication with the aperture in said plunger.

6. In a device of the class described, and in combination, an adjustable apertured ink-regulating saddle-plate adjacent to the upper side of an ink-feeding roll, of means for supporting said saddle-plate in different positions of adjustment relatively to said roll; and a tubular reservoir detachably mounted upon said saddle-plate in communication with the aperture therein; and gravity-actuated means for forcing ink from said reservoir through said aperture.

7. The combination with an ink-feeding roll and a bearing-frame upon which said roll is rotatively mounted, said frame having upwardly projecting brackets, of a supporting plate mounted upon the several brackets; an apertured saddle-plate adjacent to the top of said roll and substantially conforming to the rear upper side of the

roll from the horizontal plane passing through the axis of the roll to the vertical plane passing through the axis of the roll; an ink-reservoir in communication with the aperture in said saddle-plate; and screw-connections between said saddle-plate and said supporting-plate.

8. In a device of the class described and in combination, an ink-feeding roll; a vertically adjustable segmental saddle-plate substantially conforming to the upper rear side of the roll from substantially the horizontal plane passing through the axis of the roll past the vertical plane passing through the axis of the roll, the lower rear end of said plate being adapted to make substantially rubbing contact with the rear side of the roll, said plate being provided with an aperture; means for adjustably moving said saddle-plate in substantially vertical lines; and an ink-reservoir communicating with said aperture in the saddle-plate.

9. In a device of the class described and in combination, an ink-feeding roll; an apertured saddle-plate conforming to the upper side of the roll; a centrally apertured plunger mounted upon said saddle-plate in rear of the vertical plane passing through the axis of the roll in communication with the aperture in the saddle-plate; a bearing frame upon which said roll is rotatively mounted, said frame having upwardly projecting brackets; a saddle-plate-supporting plate adjustably mounted upon said brackets and offset around said plunger, said plunger being adapted to fit within an inverted ordinary ink-can-body.

In testimony whereof, I have hereunto set my hand this 29th day of September, 1913.

WILLIAM P. DELANEY.
